UNITED STATES PATENT OFFICE.

ILJA SCHEINKER, OF VIENNA, AUSTRIA.

DUPLICATING MACHINE.

Application filed March 6, 1925. Serial No. 13,506.

To all whom it may concern:

Be it known that I, ILJA SCHEINKER, merchant, a citizen of the Republic of Austria, residing at Vienna, VII, Kandlgasse 6, Austria, have invented certain new and useful Improvements in Duplicating Machines, of which the following is a specification.

This invention relates to duplicating machines having an automatic colour feed of the known type which is arranged under the matrix or stencil in the interior of the apparatus.

The known devices of this kind have the disadvantage that the inking roller is formed to act as a pressure roller and operates against a plate placed externally on the duplicating paper which is laid on the matrix or stencil. This construction does not ensure the production of fully uniform and perfect duplications.

According to this invention this disadvantage is eliminated by the fact that above the inking roller an adjustable pressure roller is provided to exert a regular pressure on the matrix or stencil. The colouring device, arranged underneath the matrix or stencil, and consisting of the ink distributing roller and the inking roller, is advantageously carried in a slide with the pressure roller situated above the matrix or stencil and the inking roller; this slide can be moved backwards or forwards, whereby the lateral guides of this slide may preferably be formed on the gear rack system in order to rotate the inking roller and thus the whole single colouring device, by its backward and forward movements.

Owing to the fact that the separate pressure roller is lodged immediately above the inking roller and operates with an external adjustable pressure against the matrix or stencil, and thus on the sheet of paper placed between, a thoroughly uniform pressure is maintained, suitable for single colour purposes, producing perfectly even copies. The paper is also kept away from the single colouring device and smudging is avoided.

One form of the invention is shown in the drawing in which—

Fig. 1 shows the duplicating machine in elevation, partly in section,

Fig. 2 is a plan,

Figs. 3 and 4 show side and front elevations partly in section of a modified adjusting device for the pressure roller.

The whole device is enclosed in a casing which can be covered by a lid, not shown in the drawing. The side walls of the casing are provided with guide rails 2 in which a slide 3 can be moved backwards and forwards by means of a handle 4. The upper rail of the guides 2 is provided upon its underside with a rack 5 into which engage the teeth of a gear wheel 6 rotatably carried on the slide 3, this gear wheel being rigidly connected with the spindle 7 of the inking roller 8. The ink squeezing and distributing rollers 9 are pressed against the inking roller 8 by means of a spring 10 which connects the spindles of the rollers 9 borne in the slot 11. The pressure roller 13 is borne in the slot 12 of the slide 3 above the inking roller 8 and is pressed upwards by a spring 14. Working against this spring the pressure roller can be pressed against the inking roller by means of the screws 15 the nut for which is formed in the upper cross plate 15¹ of the slide 3. A piece of silk gauze 17 is stretched in a frame 16, between the rollers 8 and 13, and on this the stencil is placed. The sheet of paper on which the duplicating is to be done is then placed on the stencil. Disposed at one end of the frame 16 is a flap 18 attached as by a hinge, and when this flap is raised one of the ink distributing rollers is accessible the slide being in the end position. In this position the ink can be spread from a tube or the like on the roller 9.

If, after raising the pressure roller 13, by means of the handle 4, the slide 3 is moved several times backwards and forwards, the rollers of the single colouring device will be rotated by the rack 5 causing them to squeeze the ink evenly applied to the roller 9 and to spread it on the roller 8. The machine is now ready for duplicating and the pressure roller 13, after adjusting it by means of the screws 15, can be applied to the stencil at the correct pressure. The copies can now be produced by inserting the paper and operating the slide. If the pressure adjustment be too great or too little the correct pressure can easily be attained by loosening or tightening the screws 15.

As above mentioned the roller 13 is adjusted by means of the nuts and screws 15 in the cross-plate 15¹ of the slide. If the roller 13 has for any reason to be raised, these must accordingly be screwed upwards and be again adjusted to the matrix for

a subsequent production of copies, when it may happen that this adjustment of the two screws is not evenly done so that the writing or the like is not reproduced evenly on the duplicates.

In order to obviate this fault the adjustment of the roller 13 is effected as shown by Figs. 3 and 4.

The adjusting screws 15 in this case pass loosely through the cross-plate 15¹ of the slide 3 and are supported at their lower ends by the small bearing blocks 19 of the roller 8. To the adjusting screws 15 a bracket 20 is adjustably attached, which may advantageously be passed between guides 22 of the slide 3. Eccentric cam levers 23 act on this bracket 20, being carried on a shaft borne on the slide, which shaft can be operated by a hand lever 24. This passes outwardly through a slot 25 in the cross-plate 15¹ thus fixing the two limits of the hand lever 24. If the latter be brought to its lowest position the cams 23 press the bracket 20 and with it, by means of the screws 15, the roller 13 also, downwards against the matrix. On raising the hand lever 24 to the position indicated by dotted lines the roller and with it the bracket are raised upwards by the spring 14.

When once the bracket 20 on the screws 15 is adjusted to the required pressure on the roller 13, this pressure remains unaltered after lowering the hand lever 24, even if the roller 13 be repeatedly raised. Therefore after the roller 13 has once been adjusted, even though it be raised repeatedly, clear and evenly inked copies will always be produced, in addition to which the loss of time which would otherwise be inevitable, owing to the necessity for the readjustment of the screws 15 each time after the roller is raised, is obviated.

The present invention can also be applied to rotary printing devices.

Having now particularly described and ascertained the nature of my said invention and in what manner the same is to be performed, I declare that what I claim is:

1. In a duplicating machine, the combination of a frame adapted to support a matrix or stencil, inking mechanism including an inking roller rotatable below said matrix, a pressure roller above the matrix or stencil

in vertical axial alinement with said inking roller, and means for adjusting the pressure of the pressure roller against the inking roller.

2. In a duplicating machine, the combination of a frame adapted to support a matrix or stencil, a horizontally reciprocable carriage, inking mechanism supported by said carriage, said inking mechanism including an inking roller rotatable in contact with the under face of said matrix or stencil, a pressure roller supported by said carriage over the upper face of the matrix or stencil in vertical axial alinement with said inking roller, and means for adjusting the pressure of the pressure roller against the inking roller.

3. In a duplicating machine, the combination of a frame adapted to support a matrix or stencil, a horizontally reciprocable carriage, inking mechanism supported by said carriage, said inking mechanism including an inking roller rotatable in contact with the under face of said matrix or stencil, a pressure roller supported by said carriage over the upper face of the matrix or stencil in vertical axial alinement with said inking roller, a spring tending to raise said pressure roller from the matrix or stencil, and means for pressing the pressure roller against the action of the spring into adjusted pressing relation with the inking roller.

4. In a duplicating machine, the combination of a frame adapted to support a matrix or stencil, a horizontally reciprocable carriage, inking mechanism supported by said carriage below the matrix or stencil, said inking mechanism including an inking roller in contact with the under face of the matrix or stencil, a pressure roller supported by said carriage above the matrix or stencil in vertical axial alinement with the inking roller, a spring tending to raise the pressure roller from the matrix or stencil, screws for adjustably pressing the pressure roller against the upper face of the matrix or stencil into pressing relation with the inking roller, a bracket through which said screws pass, and means for uniformly moving said bracket and the said screws.

In testimony whereof I affix my signature.

ILJA SCHEINKER.
